SAMUEL RUBEN, OF NEW YORK, N. Y., ASSIGNOR TO RUBEN PATENTS COMPANY, OF NEW YORK, N. Y., A CORPORATION OF DELAWARE

METHOD AND APPARATUS OF TELEPHONIC COMMUNICATION

Application filed April 8, 1922. Serial No. 550,850.

This invention relates to an apparatus for producing acoustic vibrations of a gas in response to variations in a thermionic discharge as controlled by electrical oscillations at 5 audio frequency, impressed upon the electrical circuit of a thermionic emission element. The sound waves electrically transmitted by the commonly employed telephone systems of communication are reproduced by electrically 10 moving or vibrating a diaphragm at a rate corresponding to the variations in the current actuating an element in the circuit, such as an electro magnet, the vibrations of the diaphragm, causing the surrounding gas to 15 vibrate; thus partially reproducing the transmitted waves. In all of such systems there is a distortion of the qualities of the transmitted sound due to the incapacity of the diaphragm to vibrate to the full range of frequencies and 20 other characteristics of the sound waves.

By this invention, no such physical limitations exist; there are no diaphragms or other movable mechanical elements. Broadly, this apparatus is composed of a thermionic 25 emission element and a cooperating anode element closely spaced therefrom, with means for varying the volume of partially confined gas within the space, in acoustic vibrations in response to potential variations of a current at audio frequency impressed upon the cathode-anode circuit.

The gas in the thermionic field of the receiving apparatus expands and contracts in response to audio frequency current variations 35 applied to its circuit, due to the expenditure upon the conductive field of the energy induced by the current variations. The effect of such electrical impulse variations upon the 40 conductive field of the receiving apparatus is the emission of sound waves.

It is therefore a principal object of this invention to utilize electrical impulses at audio frequency impressed upon a gas in the field 45 of a thermionic discharge, to produce acous-

tic vibrations of that gas, with minimum distortion and loss of energy.

When electrodes are connected in a circuit and a potential applied to them, one or both being sufficiently heated and the cathode preferably coated with an oxide of high electronic emission, there will be a conductive current, or thermionic discharge, through the conductive field or space between them. The gas in the field is thus ionized and heated by that discharge. While the ionizing means described is useful and of practical form, efficient ionization may be had by other means, such as by a flame.

An apparatus constructed according to the terms of this invention comprises broadly, a cathode with means for heating it to an emission temperature and, closely spaced from it, an anode connected to it in an external circuit, and thermally and electrically insulated, the partially closed restricted space between those elements opening into a sound directing device, means being provided for impressing electrical impulses upon the ionized circuit. In one practical form of the invention, the cathode, or emission element is in a partially closed vessel, and is exteriorly coated with an alkaline earth oxide, and closely spaced from the anode element. As the cathode is sufficiently heated and a high potential is maintained between those elements, the gas in the intervening space is rarefied and ionized. The volume of gas varies with its temperature and with the current discharging through it, the discharge varying with the electrical impulses impressed upon the anode circuit, the response to which is acoustic vibrations or sound waves emitted according to the gas movement into and from the restricted space. That is, as variations occur in the potential between the electrodes in response to variations in the electrical impulses impressed upon the anode circuit, corresponding variations occur in the gas volume in the field of the thermionic discharge,

the gas expanding and contracting in the same frequency and with the same characteristics as those of the applied potential, and thereby producing corresponding acoustic vibrations, which are emitted through a direct-
5 ing funnel or horn.

In the drawings referred to,

Fig. 1 is a diagrammatic illustration of the apparatus in a wire circuit, showing the arrangement of the electrodes in the transmitter and in the receiver apparatus.

Fig. 2 represents the same system and apparatus, with the addition of an amplifying means in the circuit.

In Fig. 1, 1 shows one of the electrodes in the transmitter, or sound receiving device of the system, in the form of a gauze plate; 2 represents the ionizing element, an alkaline earth oxide coated platinum wire, its source 20 of heat being represented by 3, and 4 is the source of potential applied to the electrodes for the discharge through the thermionic field. The transformer is 5, the secondary of which is connected to the receiving or sound emitting device of the system, 6 being the ionizing element of the opposing electrodes, 7 being an electrode in the form of a plate, and 8 the source of energy of the ionizing element.

In Fig. 2, 9 is a transformer, the secondary of which is connected to the electrodes, 6 and 7, in the receiver housing, the primary of this transformer being connected to a vacuum tube amplifier, 11, such as is commonly used 35 for this purpose, the source of potential there-
for, being battery, 10, the energy for the emis-
sion element being supplied by battery, 12,
and 13 being the resistance for the control
of the current of that element. 14 represents
40 the housing for the transmitter and 15, the
housing with its horn for the receiver, and
16 represents the point at which an amplifying
means can be connected in a wire circuit
if a receiver is to be employed independently
45 of the transmitter.

In operation, referring to Fig. 1, when the ionizing element 2 is heated by battery 3 and a potential is applied by battery 4 across the elements 1 and 2 through the primary of 50 transformer 5, the gas between the electrodes is ionized, and a current flows through the gaseous field thereof.

Pressure fluctuations occur in the electrically conductive gaseous field between electrodes 1 and 2 in response to the sound waves 55 impressed thereupon through the gauze electrode 1, the conductivity of that field varying accordingly. These fluctuations affect the field potential and, correspondingly, the current flow of the circuit of electrode 2, and are reflected through the secondary of the transformer 5, in the circuit of electrode 6, supplied by battery 8, and also in the potential 60 of the electrically conductive gaseous field of electrodes 6 and 7 of the receiver.

As that potential varies, the gas in its field responds by pressure fluctuations, or vibrations, which, having the frequency and other characteristics of the impressed sound waves are emitted through horn 15, as sounds corresponding in frequency and other characteristics, with the sound waves impressed at the transmitting end.

The operation of the circuit and apparatus shown in Figure 2 is identical with that of Figure 1, with the introduction of an amplifying means, such as is commonly used for this purpose, between the transmitter and the receiver.

The drawings show the invention as applied to a wire circuit telephonic communication system. It can be applied to various uses, such as radio communication, employing both the transmitter and the receiver, or either device. The receiver can, by amplification, be made into a loud speaking device. This form of audio receiving device can be substituted for the commonly used type of receiver in a wire circuit or in a radio communication system.

The receiver can also be constructed for and operated by a constant discharge current between its electrodes. An electrically charged grid or a magnetically operated element inserted in the discharge field, will, with changes in its potential, affect the discharge accordingly, the gas responding in sound wave vibrations.

What I claim is:

1. An electrical sound emitting apparatus comprising a gas filled container having a sound opening, a hot cathode and anode within said container arranged to effect ionization of the gas therein, means for discharging a thermionic current through said gas, and means for varying the discharge in accordance with audio signal currents.

2. An electrical sound emitting apparatus comprising a gas filled container having a sound opening, a cathode and an anode within said container arranged to effect ionization of the gas therein, means for discharging a thermionic current through said gas, means for varying the discharge in accordance with audio signal currents, and means for directing acoustic vibration from said sound opening away from said apparatus.

3. An electrical sound emitting apparatus comprising a housing having an opening and arranged to form an enclosure communicating with the atmosphere through the said opening only, a pair of electrodes situated within the enclosure, means for producing a thermionic discharge between said electrodes, and means for varying the density of said discharge in accordance with audio signal currents.

4. An electrical sound emitting apparatus comprising a housing having an opening and arranged to form an enclosure communicat-

ing with the atmosphere chiefly through the said opening, an ionic discharge device situated within the enclosure, a grid-form control element situated within the enclosure between the discharge device and the opening, and means for varying the potential between the discharge device and the control element in response to audio signal currents.

5. An electrical sound emitting apparatus comprising a housing having a sound opening therein, an ionizing electrode and a co-operating electrode situated within the housing, a circuit for said electrodes, and means for imposing current variations on the circuit of said electrodes corresponding to the sounds to be emitted.

6. An electrical sound emitting apparatus comprising an ionizing electrode and a co-operating electrode spaced therefrom with an intervening ionizable fluid, and means for varying the potential between the electrodes in accordance with audio-signal currents to produce corresponding variations in pressure in the intervening fluid.

25. 7. An electrical sound emitting apparatus comprising a partially confined fluid body, an ionizing element and a control element in contact with said fluid body, and means for varying the potential between the ionizing 30 and control element in accordance with electrical audio signaling currents.

8. An ionic discharge acoustic translating device comprising a housing having a sound opening therein, an ionic discharge device situated within the housing, and a grid-form control element situated within the housing between the discharge device and the opening.

9. The method of translating audio electrical signal currents into acoustic vibrations 40 of the atmosphere which comprises varying the potential between a hot cathode and an anode in accordance with the variations of the signal currents while surrounded by a 45 partially confined gaseous body to produce corresponding variations in pressure in said confined gaseous body, and communicating said variations in pressure to the atmosphere.

10. The method of translating audio electrical signal currents into acoustic vibrations 50 of the air which comprises ionizing between a hot cathode and an anode, a partially confined body of atmospheric air, and varying the potential between the cathode and anode 55 in accordance with the variations of the signaling currents to produce corresponding variations in pressure in said fluid.

11. Means for reproducing sound through 60 the medium of an ionized air gap which comprises a hot cathode and a cold anode separated therefrom and exposed to atmosphere, a source of current for said cathode, and means for impressing a current varying in potential in accordance with the sound to be re-

produced, upon the space between said cathode and anode.

12. Means for reproducing sound comprising a long cathode strip and a long anode strip separated therefrom, and means for ionizing the air between said cathode and anode in accordance with the sounds to be reproduced.

13. Means for reproducing sound through the medium of an ionized air gap which comprises a long cathode strip and a long anode strip separated therefrom, a source of current for said cathode, and means for impressing a current varying in potential in accordance with the sounds to be reproduced upon the space between said cathode and anode.

14. Means for reproducing sound comprising a hot cathode and a cold anode separated therefrom, the effective surface areas of said cathode and anode being great relative to space of separation therebetween, and means for ionizing the air between said cathode and anode in accordance with the sounds to be reproduced.

15. Means for reproducing sound through the medium of an ionized air gap which comprises a cathode and a cold anode separated therefrom, the effective surface areas of said cathode and anode being great relative to the space of separation therebetween, a source of current for said cathode, and means for impressing a current varying in potential in accordance with the sound to be reproduced upon the space between said cathode and anode.

16. Means for reproducing sound comprising a long hot cathode strip and a long anode strip separated therefrom, and means for ionizing the air between said cathode and anode in accordance with the sounds to be reproduced, said cathode and anode being located in the open air.

17. Means for reproducing sound through the medium of an ionized air gap which comprises a long hot cathode strip and a long anode strip separated therefrom, a source of current for said cathode, and means for impressing a current varying in potential in accordance with the sounds to be reproduced upon the space between said cathode and anode, said cathode and anode being located in the open air.

18. Means for reproducing sound comprising a hot cathode and a cold anode separated therefrom, the effective surface areas of said cathode and anode being great relative to space of separation therebetween, and means for ionizing the air between said cathode and anode in accordance with the sounds to be reproduced, said cathode and anode being located in the open air.

19. Means for reproducing sound through the medium of an ionized air gap which comprises a cathode and a cold anode separated therefrom, the effective surface areas of said
